UNITED STATES PATENT OFFICE.

JOSEPH JUDGE, OF PITTSTON, PENNSYLVANIA.

SAFETY DEVICE FOR AIR-BRAKES.

No. 839,598.

Specification of Letters Patent.

Patented Dec. 25, 1906.

Application filed August 28, 1906. Serial No. 332,335.

To all whom it may concern:

Be it known that I, JOSEPH JUDGE, a citizen of the United States, and a resident of Pittston, in the county of Luzerne and State of Pennsylvania, have invented a new and Improved Safety Device for Air-Brakes, of which the following is a full, clear, and exact description.

My invention relates to means for applying the air-brakes to the cars of a train, and has for its object to provide a device simple in construction, positive in action, and not liable to become inoperative, and adapted to insure proper observance of a danger or other signal designed for the engineer of a train. This I accomplish by the means illustrated in the drawings, in which drawings like characters of reference indicate like parts throughout the views, and in which—

Figure 1 is a side elevation of a device embodying my invention applied to the cab of an engine. Fig. 2 is a plan view, partly in section, taken on the line 2 2 of Fig. 1. Fig. 3 is a sectional elevation of a swivel-valve connected with the train air-pipe, shown in side elevation; and Fig. 4 is a vertical section taken on the line 4 4 of Fig. 1.

As illustrated in the drawings, 1 represents a train air-pipe extending upward into the cab and provided with an elbow 2, connected with a horizontal extension 1^a of the train-pipe. The train-pipe is connected by means of such extension with a swivel-valve, the lower portion 3 of which consists of a standard having a cylindrical hollow end-closed stem 3^a extending upward therefrom and provided with a lateral port 3^b. The upper portion of the valve consists of a sleeve 4, which is rotatably mounted upon the stem 3^a and provided with an opening 4^a and a lateral extension or nipple 4^b, threaded interiorly to engage a corresponding exteriorly-threaded end of a pipe 5. The sleeve 4 of the upper portion of the valve is held in close engagement with the stem 3^a of the lower portion of the valve by means of a washer 4^c and set-screw 4^d, secured to the closed upper end of the sleeve 3^a. The pipe 5 is threaded on its outer end, so as to engage a threaded flange 7^a, formed on a sleeve 7. The outer end of the sleeve 7 is threaded to engage a gland 8 and is provided with an annular flange 8^a, adapted to bear against a ring of packing 9, arranged within the gland between the flange of such gland and offset end 6^a of a frangible tube 6, which is secured

within the sleeve 7 and gland 8. A similar ring of packing 9^a is arranged between the offset end 6^a of the tube 6 and the flange 7^a of the sleeve 7. By means of such construction a tight joint is maintained between the pipe 5 and the frangible tube 6. An arm 10 is formed on or secured to the sleeve 4 of the upper portion of the valve, and a link 11 is pivoted to the outer end of said arm by means of a pin 10^a. The opposite end of said link is pivoted to a lever 12 by means of a hinge-pin 11^a. The lever 12 is rigidly secured to a spindle 13, which is rotatably mounted in a vertical casing 16, secured to a bracket or shelf 19, attached to the cab and provided with a flange 16^a, adapted to bear against the upper surface of the shelf 19 and secured thereon against a rotary movement by means of screws 16^c. A pin 16^d is secured to an offset arm 16^b, formed on the upper end of the casing 16, and engages the outer end of a spring 15, the opposite end of which spring is secured to a pin 12^a, attached to the end of the lever 12. The spring 15 normally presses the outer end of the lever 12 forward and the link 11 connected therewith, which in turn presses forward the outer end of the arm 10, attached to the casing of the upper portion of the valve, and holds the pipe 5 and frangible tube 6 outward from the cab and at a right angle thereto.

A lever 14 is rigidly secured to the lower end of the spindle 13, so that by moving such lever horizontally the spring 15 is compressed, the outer end of the lever 12 moved backward, carrying with it the link 11 and outer end of the arm 10^a, so as to draw inward the pipe 5 and frangible tube 6, connected therewith, into the position indicated by dotted lines in Fig. 2. An opening 20 is made in the side of the cab to permit such inward movement of the pipe 5. The inward movement of such pipe is limited by means of a stop 21, and a stop 22 limits the outward or backward movement of said pipe. A wing 17 may be secured to the pipe 5, so that the current of air generated by the movement of the train will aid in holding the pipe 5 in a backward and outward position in case the spring should become broken or inoperative. By means of such construction a constant communication between the train air-pipe 1 and the frangible tube 6 is maintained while the tube extends outward from the cab of the engine. This is accomplished by means of the port 3^b, formed in the stem

- 3^a of the valve, which registers with the opening 4^a, formed in the sleeve 4 of the valve, when the frangible tube 6 extends in such outward direction. By moving the lever 14 horizontally, however, the spring 15 is compressed so as to draw backward the outer end of the lever 12 and the arm 10, secured to the casing 4, so as to bring the opening 4^a of such sleeve out of alinement with the port 3^b of the stem of the lower portion, and thereby close the port 3^b of the valve. When, however, the frangible tube 6 extends outward from the cab of the engine and is struck by any obstacle so as to fracture the tube, the air is permitted to escape from the train air-pipe, thereby setting the air-brakes. Arms 18 are preferably attached rigidly to the standard of a semaphore-signal and are arranged in the path of travel of the frangible tube 6, and unless such tubes are moved inward before approaching the arm of the semaphore-standard by moving horizontally by hand the lever 14, the tube 6 will be fractured by the arm of the semaphore-standard and set the air-brakes of the train. If an engineer, therefore, passes a semaphore-signal without observing it and moving the frangible tube 6 out of the way of the arm, the brakes are automatically applied and the train stopped. Instead of attaching such arms to the standards of a semaphore-signal the arms may be rigidly secured to standards placed along the line of the railroad at regular intervals of one or more miles and arranged to extend in the path of travel of the tube 6, so as to stop the train automatically if the engineer should become disabled from any cause.
- In the drawings a device embodying my invention is shown supported upon a shelf secured to the side of the cab of an engine, with the pipe 5 extending through an opening in said cab. In most instances, however, I prefer to arrange said device on the outside of the top of the cab, with the handle 14 arranged within the cab, so as to be readily operated by the engineer.
- Having thus described my invention, what I claim as new, and desire to secure by Letters Patent, is—
1. The combination with a train air-pipe, of a swivel-valve connected therewith, a pipe connected with the swiveling portion of the
- 55 said valve, a frangible tube connected with said pipe, a rocking spindle provided with an arm, a spring connected with the end of said arm, a link connection between said spindle and the swiveling portion of the valve, and a lever adapted to rock said spindle, substantially as shown and described.
- 60 2. The combination with a train air-pipe, of a swivel-valve connected therewith, a pipe secured to the swiveling portion of said valve, a frangible tube connected with said pipe, and spring mechanism connected to the swiveling portion of the valve so as to hold the frangible tube in a predetermined position, substantially as shown and described.
- 65 3. The combination with a train air-pipe, of a swiveling valve connected therewith, comprising a hollow stem provided with a port and a sleeve journaled on said stem and provided with a hollow nipple having an opening adapted to register with the port of said stem, a pipe secured to said nipple, a frangible tube secured to said pipe, spring-actuated mechanism adapted to keep the port of said stem in alinement with the opening of said nipple, and a lever adapted to control said mechanism, substantially as shown and described.
- 70 4. The combination with a train air-pipe, of a swivel-valve connected therewith, a frangible tube connected with said valve, and spring mechanism adapted to hold said tube normally in a predetermined position, substantially as shown and described.
- 75 5. The combination with a train air-pipe, of a swivel-valve connected therewith, a frangible tube connected with said valve, a spring mechanism adapted to hold said tube normally in a predetermined position, and a lever adapted to operate said valve, substantially as shown and described.
- 80 6. The combination with a train air-pipe, of a swivel-valve connected therewith, a frangible tube connected with said valve, and a wing connected with said frangible tube, substantially as shown and described.
- 85 In testimony whereof I have signed my name to this specification in the presence of two subscribing witnesses.
- 90 JOSEPH JUDGE.
